APPARATUS FOR SETTING UP FOLDING
CARTONS AND THE LIKE

Arthur J. Weiss, West Englewood, N. J., assignor
to Robert Gair Company, Inc., New York, N. Y.,
a corporation of Delaware

Application March 2, 1949, Serial No. 79,286

4 Claims. (Cl. 93—53)

1

The invention relates to apparatus for setting up folding cartons and the like.

Folding cartons of the kind commonly known in the paperboard carton trade as the "simplex" type have side walls with end extensions attached to the end walls. These end extensions have diagonal score lines, usually "pre-broken" for ease of folding during the operation of setting up the folded carton. In the flat folded carton the end walls are not folded, but are coplanar with the bottom. The side walls and side wall extensions are inwardly folded, flat against the bottom, the side wall extensions being integral with the side edges of the end walls. The diagonal score lines of the side wall extensions proceed from the corners of the bottom, defining in each extension two approximately triangular panels. As the carton is set up, substantially simultaneous erection of the side and end walls brings these triangular panels into superimposed relationship, and infolding end flaps formed as extensions of the end walls are snugged down inside the carton to hold it in its erected form.

In the operation of setting up this kind of carton, difficulty is frequently experienced by reason of the necessity for erecting the side and end walls substantially at one and the same time. This is particularly true when setting up the carton by hand. Experienced operators can do it all right, but it is a tricky manipulation and when it comes to setting up the larger sizes of cartons such as shirt boxes and other long boxes the difficulties are increased. This is particularly so when the girls who do this work have small hands and cannot reach the side wall panels with their thumbs at the same time that they are pulling in on the end walls with their fingers as is necessary with simultaneous erection of the four walls. In such a case, one end of the folded carton must be held against the operator's body, the side walls then being raised slightly while the other end is raised, the hands then being shifted quickly to complete the infolding of first one end and then the other. This takes more time because it increases the number of steps in the operation, and the manipulation reveals waste movements of the hands in working around the carton to finagle it into form.

The main object of my invention is to provide some way of simplifying the manipulation so that it can be performed with speed and ease by the less experienced operators. I have accomplished this object by a very simple form of apparatus. The apparatus does not take the place of the manual operation, but holds the carton in such

2

a manner that by a different and simpler manipulation even the largest cartons can set up rapidly and easily by almost anyone and with scarcely any preliminary training. My apparatus holds the ends of the carton raised into a slightly inclined position, i. e. the ends are "sprung" upwardly, and are so held while the operator performs the first part of the operation of erecting the side walls of the carton. Both hands are free for lifting the side walls to partly erected position. Because of the inward compressing action of my apparatus the side walls "snap" into this partly erected position and remain that way without further attention on the part of the operator. This again leaves both hands free, and the fingers or palms of the hands are pressed against the inclined ends of the carton to bring them fully erect while at the same time the infolding end flaps are pushed with the thumbs and the hands slipped inside the erected carton to snug these flaps into their final locking position.

My apparatus, in its general arrangement, comprises spaced fingers and supporting arms arranged to cradle the folded carton, the fingers being arranged to be brought into a position such that they are spaced apart by a distance less than what would be the length of the folded carton if it were lying flat, i. e. by a distance less than the length of the "flat-folded" carton when perfectly flat. This arrangement provides a cradle for the folded carton, or for a stack of folded cartons, having a substantially flat central portion and inclined ends with vertical retaining fingers or brackets on the inclined ends adapted to hold the folded cartons with their ends sprung upwardly.

In order to assist others in practicing my invention and in obtaining its fullest advantages, I shall here describe what I now consider to be its best embodiment. In the drawings, which illustrate this embodiment:

Fig. 1 is a side elevational view of the apparatus, partly broken away in vertical cross section, with a folding carton in place and ready for setting up.

Fig. 2 is a top plan view of the same, but with the carton removed.

Fig. 3 is a transverse vertical cross sectional view, taken on the line 3—3 of Fig. 1, but with the carton removed.

Figs. 4, 5 and 6 are perspective views illustrating the operation of setting up one form of carton with use of the apparatus shown in Figs. 1—3.

Referring to Figs. 1 to 3, the preferred form of apparatus will be seen to comprise two pairs of opposed brackets 7 mounted on a base or table 8. These brackets have portions 9 inclined outwardly and upwardly. Mounted on the inclined portions of the brackets 7 are retaining brackets 10 carrying vertically arranged fingers 11 with opposed serrated surfaces 12 for engagement with the respective ends of a folded carton C, or a series or "stack" of such cartons. The construction described forms a cradle having a substantially flat central portion and inclined ends with vertical retaining brackets on the inclined ends adapted to hold a stack of molded paper board cartons or the like with their ends "sprung" upwardly.

I prefer to have at least one of the sets of brackets 7 (i. e., at least one of the brackets of each pair) adjustable to permit variation of the distance between the fingers 11 of each pair. Also I prefer to have the brackets 10 adjustable. These adjustments allow the adaptation of the device for use with cartons of different sizes and proportions, although of course no adjustment need be provided if the device is to be used exclusively in setting up just one size and design of carton. In general, the adjustment will be such that the flat central portion of the cradle will be substantially equal in length to the length of the bottom of the carton, and the distance from the fingers 11 to the point where the inclined ends of the cradle adjoin its flat central portion will be substantially equal to the height of the carton ends.

In the preferred apparatus shown, these adjustments are provided in the manner now to be described. Base 8 has a pair of channels 13 in its upper surface, the width of these channels being about equal to the width of brackets 7, and their depth about equal to the thickness of the brackets so the brackets will be slidably received in the channels and be flush with the base. Slots 14 in the base 8, in line with channels 13, accommodate clamping screws 15 which cooperate with the horizontal portion of each bracket 7 and a clamping plate 16 in holding the bracket in its selected position of adjustment. Clamping plates 16 are slidably carried in channels 17 in the underside of the base 8 paralleling channels 13. When the screws 15 are loosened, the brackets 7 and plates 16 can be moved along their respective channels to adjust the distance between the brackets of each pair to a position in which the flat central portion of the cradle will be substantially equal to the length of the bottom of the carton C.

The inclined portion 9 of each bracket 7 is slotted as at 18 to receive a threaded stud 19 mounted on the bracket 10. A wing nut 20 serves to clamp bracket 10 in its selected position of adjustment, such that the distance from finger 11 to the point where the inclined end of the cradle adjoins its flat central portion will be substantially equal to the height of the ends of the carton C.

In Figs. 4, 5 and 6, I have illustrated the operation of setting up one form of carton with the use of my apparatus. For simplicity of illustration, the apparatus itself is not shown in these views, but it will be understood that the carton is resting in the cradle. In Fig. 4, the carton is considered as being held between the serrations 12 of fingers 11 exactly as shown in Fig. 1. Carton C which I have selected for illustration, is of the kind commonly known in the paperboard carton business as the "simplex" type. While I

refer to this as a carton, it has a construction which also may be used, and frequently is used, as a cover for a carton. Also it may be put to other uses such as display baskets, etc. For simplicity, I will continue the description by reference merely to a "carton" or "carton and the like."

A "carton" of the particular type here illustrated has a bottom panel with adjoining side walls 21, end walls 22 and infolding end wall extensions 23. Side wall extensions 24 are integral with both side and end walls, adjoining the side walls 21 at fold lines 25 and the side edges of the end walls 22 at fold lines 26. Fold lines 26 are in line with the fold line between the side walls and the bottom of the carton. End extensions 24 have diagonal score lines 27, usually "pre-broken" for ease of folding during the operation of setting up the carton. In the flat folded carton the end walls are not folded but are coplanar with the bottom. The side walls and side wall extensions are inwardly folded, flat against the bottom, substantially as shown in Fig. 4, except that the ends of the carton lie down flat instead of being sprung upwardly in the cradled position shown. The diagonal score lines 27 of the side wall extensions proceed from the corners of the bottom, defining in each extension two approximately triangular panels 28 and 29. As the carton is set up, substantially simultaneously erection of the side and end walls brings these triangular panels into superimposed relationship, and the infolding end flaps 23 are snugged down inside the carton to hold it in its erected form. These flaps 23 may have extensions 24' which assist in holding them in their locking position.

When a carton of this general type is to be set up with the use of my apparatus, it is dropped into the cradle so that its ends are raised to an inclined position as shown in Figs. 1 and 4, and are held in that position during the first part of the operation of erecting the side walls of the carton. That is, the ends of the carton are sprung upwardly by reason of the compressing action exerted by the fingers 11.

In the preferred embodiment of my apparatus as illustrated, a series or "stack" of folded cartons C can be accommodated in the cradle at the same time. I prefer to handle about six cartons at a time, and in this case the operator will take the six cartons and drop them into the cradle from the top. As the cartons drop into the cradle, they will assume the position shown in Fig. 1. The operator will then begin by setting up the carton which is on the top of the stack, remove it, and work down until the last carton in the stack has been set up.

Each carton is set up substantially as follows: First the side walls 21 are raised slightly until they snap into the partly erected position shown in Fig. 5. Note that the operator has both hands free for this step in the operation. Because of the inward compressing action of the fingers 11, the side walls 21 will remain in the partly erected position of Fig. 5 without further attention on the part of the operator. This again leaves both hands free, and the fingers or palms of the hands are pressed against the inclined ends 26 of the carton to raise them in the direction indicated by the arrows 30 (Fig. 5) and bring them fully erect, while at the same time the infolding end flaps 23 are pushed with the thumbs in the direction indicated by the arrows 31 (Fig. 6); and the hands slipped inside the erected carton to snug these flaps into their locking position.

5

The last part of this operation is illustrated in Fig. 6.

From the foregoing description it will be understood that the apparatus does not take the place of the operation as previously performed by hand, but holds the carton in such a manner that by a different and simpler manipulation even the largest of cartons can be set up rapidly and easily and with very little preliminary instruction.

The term "carton" and the expression "carton and the like" as used herein and in the appended claims are intended to include both carton bodies and carton covers, having in mind that both bodies and covers may be of similar construction and that the apparatus herein disclosed is useful and advantageous in setting up both bodies and covers. Also, I include within this definition other types of folding paperboard articles such as display baskets, display stands, etc., for the invention relates to the apparatus, and it will be appreciated that this apparatus is useful in setting up folding paperboard articles of any type in which the setting up operation is facilitated by springing up the ends of the folded article and holding them so during a subsequent step or manipulation affecting other elements of the article being operated on. All of the terms and expressions which I have employed are used in a descriptive and not a limiting sense, and I have no intention of excluding such equivalents of the invention described, or of portions thereof, as fall within the purview of the claims.

I claim:

1. A cradle for setting up folding cartons and the like, comprising a base member, pairs of

6

opposed brackets mounted on said base member, said brackets having portions inclined outwardly and upwardly, and fingers mounted to be clamped in fixed operating position on said inclined portions of the brackets for engagement with the respective ends of the folding carton.

5 2. A cradle as defined by claim 1 in which said fingers have vertically arranged serrated fingers to permit a stack of folded cartons to be dropped between them in superimposed relationship with the serrated surfaces in engagement with the respective ends of the cartons in the stack.

10 3. A cradle for setting up folding cartons and the like, comprising a base member, opposed brackets mounted on said base member, said brackets having portions inclined outwardly and upwardly, and fingers mounted to be clamped in fixed operating position on said inclined portions of the brackets for engagement with the respective ends of the folding carton.

15 4. A cradle as defined by claim 3 in which said fingers have vertically arranged serrated fingers to permit a stack of folded cartons to be dropped between them in superimposed relationship with the serrated surfaces in engagement with the respective ends of the cartons in the stack.
